UNITED STATES PATENT OFFICE.

CONSTANT T. PARARO, OF BENHADEN, FLORIDA.

DESIGN FOR A SPIKE-GRIPPING TOOL.

47,046.

Specification for Design.

Patented Mar. 2, 1915.

Application filed October 31, 1914. Serial No. 809,710. Term of patent 14 years.

To all whom it may concern:

Be it known that I, CONSTANT T. PARARO, a citizen of the United States, residing at Benhaden, in the county of Wakulla and State of Florida, have invented a new, original, and ornamental Design for Spike-Gripping Tools, of which the following is a specification, reference being had to the accompanying drawing, forming a part thereof.

The figure is a perspective view, illustrating my design.

I claim:

The ornamental design for a spike gripping tool, as shown.

CONSTANT T. PARARO.

Witnesses:

HENRY S. QUARTERMAN,
W. F. ROBERTSON.
